ANKLE WEIGHT FOR ATHLETES

Elmer L. Tarbox, Box 5426, Lubbock, Tex.

Filed Apr. 2, 1959, Ser. No. 55,325

Term of patent 14 years

(Cl. D34—5)

Fig. 1

Fig. 2

Fig. 3

FIGURE 1 is a rear perspective view of an ankle weight for athletes, embodying my new design.

FIGURE 2 is an extended elevational view thereof, and

FIGURE 3 is a front perspective view of the ankle weight for athletes shown in FIG. 1.

I claim:

The ornamental design for an ankle weight for athletes, substantially as shown.
